UNITED STATES PATENT OFFICE.

COCIU ENACHE, OF DALLAS, TEXAS.

RAILWAY SAFETY GATE.

Application filed July 28, 1923. Serial No. 654,313.

To all whom it may concern:

Be it known that I, Cociu ENACHE, a citizen of the United States of America, residing at Dallas, in the county of Dallas and 5 State of Texas, have invented certain new and useful Improvements in Railway Safety Gates, of which the following is a specification.

This invention relates to new and useful 10 improvements in railway safety gates.

The object of the invention is to provide certain improvements as well as additions to the gate covered by my Letters Patent No. 1,394,813, issued Oct. 25, 1921.

15 One of the improvements consists in eliminating the grooves in the head of the rail and reducing the number of parts.

A further object is to simplify the gate structure.

20 Another object of the invention is to provide an automatic safety gate that will be comparatively simple, efficient and practical as well as reliable.

A construction designed to carry out the 25 invention will be hereinafter described together with other features of the invention.

The invention will be more readily understood from a reading of the following specification and by reference to the accompanying drawings, in which an example of the 30 invention is shown, and wherein:

Fig. 1 is a plan view of an apparatus constructed in accordance with my invention,

Fig. 2 is a side elevation of the same,

35 Fig. 3 is a detail of one of the slide bars,

Fig. 4 is a plan view of the operating means for closing the gates,

Fig. 5 is a side elevation of the same,

40 Fig. 6 is a detail of the gate swinging elements,

Fig. 7 is a section on the line 7—7 of Fig. 6,

Fig. 8 is a side elevation of one of the gates in its closed position,

45 Fig. 9 is a cross-sectional view taken on the line 9—9 of Fig. 8, and

Fig. 10 is a cross-sectional view taken on the line 10—10 of Fig. 8.

In the drawings the numeral 10 designates one of the rails and 11 the other rail of a railway track. At the crossing over the track I arrange four gates, two on each side of the track swinging toward each other. Each gate includes an upright yoke 12 (Fig. 55 8) which is rigidly mounted. Journaled at

its upper and lower ends in said yoke is a post 13 to which is hinged a gate panel 14. The gate panel has an outer hinged section 15 provided with trunnions 16 journaled in arms 17 extending from the panel proper. The arms have stop lugs 18 projecting in the path of section 15 whereby the latter may swing inwardly, but not outwardly.

When the gate is closed it is desirable to lock the section 15 against swinging inwardly also and a slidable bolt 19 is provided for the purpose. The bolt 19 is mounted to slide in brackets 20 mounted on the section 14, and having its end engaging in a keeper 21 on the section 15. A coiled 70 spring 22 connected with the bolt and the innermost bracket 20 tends to pull the bolt from the keeper. On the yoke I mount a stop arm 23 having a cam face 24 reducing to a point at the free end of the arm. The bolt has a slot 19' (Fig. 10) and the end of the arm enters said slot when the gate approaches the end of its closing movement.

It will be seen that normally and during the greater portion of the swinging movement of the gate, in closing, the spring 22 will hold the bolt retracted, from the keeper 21, but when the gate closes the cam 24 will ride into the slot 19' and slide the bolt into the keeper. When the gate is opened the bolt will be carried away from the cam and thus if a vehicle was near the gate, the section would be released after the initial opening swing of the gate and this section would yield upon striking the vehicle and prevent injury thereto. The gate being hinged to swing outwardly, when closed, it will be seen that a vehicle caught on the track may continue and drive through the gates. The arm also acts as a stop because the cam does not go all the way through the slot 19'.

For swinging the gates I provide train operated means. Each post 13 has pivoted in the lower portion thereof, the end of a link 25 (Figs. 6, 8 and 10). The other end of each link is pivoted to a slide 26 confined on the side of the adjacent rail. A pair of bridle bars 27 have their ends 27' (Fig. 7) looped under the rails 10 and 11 and fastened to the slides. A pull rod 28 is connected 105 with the right hand slide (Fig. 1) of rail 10 while a second pull rod 28' extending in the opposite direction is connected to the left hand slide of rail 11. The means for operating the rods is duplicated.

An actuating bar 29 has its end attached to one of the bridle bars 27 and passes under the other bridle bar; while a second actuating bar 30 extending from the opposite direction passes under one of the bridle bars and is attached to the other bridle bar. Braces 31 are provided between the actuating bars and the bridle bars as is shown in Fig. 1. A pitman 32 is pivoted to the left hand bar 27 (Fig. 1) and has its opposite end pivoted to a centrally pivoted lever 33, having its opposite end pivoted to the bar 30. The bars 29 and 30 operate independently and oppositely, but it will be seen that when one bridle bar is moved by one of the slides 26, the lever 33 and pitman 31 will cause the movement of the other.

The rods 28 and 28' are used to close the gates and the bars 29 and 30 are actuated to open the gates. The means to pull the rods is located on each side of the crossing so as to be operated by trains approaching from either direction. At a suitable distance from the crossing a tripping lever 34 (Figs. 4 and 5) is pivoted inside the rail 10 on a bracket 35 secured to one of the cross-ties. The lever is held contiguous to the head of the rail by a spring keeper 36, so as to be depressed by the flanges of the wheels 30 of the locomotive. The swinging end of the lever is offset and bifurcated for pivotally receiving the upper end of a bell crank lever 37 mounted under the track on a hanger 38 in a casing 43.

When the lever 34 is depressed the lever 37 is swung, its lower end being swung away from the crossing. A link 39 connects the lower end of the lever 37 with a finger 40 depending from the end of the rod 28, which is pulled thereby. The rod has slots 42 receiving studs 41 extending from the web of the rail, whereby said rod is slidably supported. The rod includes a slip joint formed by ears 44 connected by a bolt 45 loose therein. This divides the rod into two sections, one of which is connected with the link 39 and the other of which is connected with the right hand slide 26 (Fig. 1). It will be understood that the rod 28' is a duplicate of rod 28 and the operating means for the same is duplicate, but when the gates are operated by one, the slip joint of the other rod prevents interference, as is indicated in Fig. 1.

It will be seen that the links 25 are connected to the posts 13, outwardly of their trunnions and consequently longitudinal movement of said links will swing the posts and the gates. When the rod 28 is pulled the bridle bars 27 are moved away from each other and a pushing movement imparted to the links 25, which swings the gates to a closed position, in which they are shown in Fig. 1.

For opening the gates the bridle bars are

moved toward each other and this exerts a pulling movement on the links 25 which swings the gates open; and the bars 29 and 30 are employed for this purpose. The bar 30 cooperates with the rod 28 and located on the opposite side of the crossing is a tripping lever 46 pivoted in a bracket 47 against the inner side of the rail 10. The lever is held against the rail by a spring keeper 48. The outer end of the lever is bifurcated and is pivoted to the upper end of a link 49, pivoted to the lower end of a bell crank lever 50 mounted in a bracket 51 in a casing 53 under the track. The upper end of the bell crank lever is pivoted to a pitman 52 which has its opposite end curved upwardly and connected with the down-turned end 30' of the bar 30. The mechanism is duplicated on the other side of the crossing and connected with the bar 29.

The operation is as follows:

A train approaching from the right (Fig. 1) will close the gates. The flanges of the wheels of the locomotive ride upon the lever 34 and depress the same whereby the bell crank lever 37 is swung, its lower end moving downwardly. The lever 37 through the medium of the link 39, pulls the rod 28, which being attached to one of the slides 26, pulls the latter. The right slide 26 (Fig. 1) being attached to the right hand bridle bar 27 pulls the latter away from the other bridle bar 27 and being attached to the bar 30 will swing the lever 33, whereby the other bar 27 is pulled away from the first bar 27, the bars 27 thus being spread apart.

The spreading of the bars moves all of the slides and each link 25 pushes on its connection with its respective gate post 13, whereby the gate is swung to a closed position. The gate panels 14 being hinged to their posts to swing outward, it will be seen that a vehicle caught on the track may pass through the gates. For swinging a gate to its normal position with relation to its post 13 I provide a flexible connection 54 attached to the panel 14 and passing under a pulley 55 on the inner end of said panel. The connection passes over a pulley 56 on the post and down to an eye 58. A coiled spring 57 is included in the connection and is tensioned when the section is swung on the post, thus returning the panel to its normal position when it is released. Normally the bolt 19 is retracted from the keeper 21 by the spring 22 on each gate, but as the gate approaches its closed position the point of the cam 24 (Fig. 10) enters the slot 19' and the bolt is thus slid into the keeper 21. The cam does not pass entirely through the slot and the arm 23 thus becomes a stop for limiting the closing movement of the gate.

When the rod 28 is pulled the slip joint in the rod 28' compensates the movement of the slide 26 to which the rod 28' is connected.

The lever 24 remains depressed until restored by a return movement of the rod 28. The gates remain closed until the last car has passed the crossing.

5. A gate opening device is far enough removed from the crossing to prevent the locomotive from reaching it until the last car has crossed. This is shown on the left hand side of Fig. 1 and includes a tripping lever 10 46 depressed by the train wheels. The lever swings a bell crank lever 50 by means of a link 52. The lever 50 pulls a pitman 52 which in turn pulls the bar 30. The bar 30 pulls the remote bridle bar 27 toward the 15 center of the crossing and swings the lever 33, whereby the nearest bar 27 is pushed toward the remote bar 27, the bars 27 thus being moved toward each other.

When the bridle bars are thus moved they 20 exert a pull on the links 25 and the latter swing the gates to an open position. After the united movement by the gates the bolts are retracted by the springs 22 and the sections 15, thus freed, so if any obstruction, 25 as a vehicle should be within the swing of the gate, the section 15 would yield and not damage or injure the same. A coiled spring 59 connecting the section 15 and the panel 14 returns the section to its normal position. 30 When the bars 27 are moved together in opening the gates a forward pull will be contributed to the rod 28, whereby the lever 34 will be restored to its elevated position.

What I claim, is:

35 1. In a railway crossing gate, a plurality of swinging gates, a sliding unit between the gates for swinging the same, a pull rod along the track for moving the unit to close the gates, a wheel operated device for pulling said rod, an actuating bar connected to the unit, and a second wheel operated device for sliding the actuating bar to slide the unit and open the gates.

40 2. In a railway crossing gate, a plurality of swinging gates, a pair of bridle bars connected with the gates for swinging them, connections between the bars for operating them in unison, train operated means for moving the bars apart to close the gates, 50 and a second train operated means for moving the bars toward each other to open the gates.

45 3. In an automatic railway crossing gate, a plurality of swinging gates arranged in pairs on each side of the track, bridle bars extending under the tracks, gate swinging means connected with the gates and the bars, means connecting the bars for moving the other bar when one bar is moved, and 55 train actuated means for operating said bridle bars for closing the gates.

50 4. In an automatic railway crossing gate, a plurality of swinging gates arranged in pairs on each side of the track, bridle bars 60 extending under the tracks, gate swinging

means connected with the gates and the bars, means connecting the bars for moving the other bar when one bar is moved, train actuated means for operating said bridle bars for closing the gates, and a second train 70 actuated means for oppositely operating said bars to open said gates.

5. In an automatic railway crossing gate, a plurality of swinging gates arranged in pairs on each side of the track, slides 75 mounted on the rails, bridle bars connecting the slides on one side with those on the other side, means for connecting the bridle bars for moving the same together with the slides in unison, operating connections between the slides and the gates for swinging the latter, and train operated means for actuating the slides to close the gates.

6. In an automatic railway crossing gate, a plurality of swinging gates arranged in 85 pairs, on each side of the track, slide mounted on the rails, bridle bars connecting the slides on one side with those on the other side, means for connecting the bridle bars for moving the same together with the 90 slides in unison, operating connections between the slides and the gates for swinging the latter, train operated means for actuating the slides to close the gates, and a second train actuated means attached to the 95 bridle bar connections for retracting the said bars to open the gates.

7. In an automatic railway crossing gate, a plurality of gates arranged in pairs on each side of the track, slides mounted on the 100 rails, bridle bars connecting the slides on opposite sides and extending under the rails, swinging connections between the slides and the gates, pulling elements mounted on the rails and connected with the slides for operating the same to close the gates, and train 105 operating means for actuating the pulling elements.

8. In an automatic railway crossing gate, a plurality of gates arranged in pairs on 110 each side of the track, slides mounted on the rails, bridle bars connecting the slides on opposite sides and extending under the rails, swinging connections between the slides and connected with the slides for operating the 115 same to close the gates, oppositely directed actuating bars crossing the bridle bars, the opposite ends of said actuating bars, a centrally pivoted lever connected with one of the actuating bars, a pitman connected with 120 said lever and also to the adjacent bridle bar, a train depressed element for actuating the pulling elements, and a second train depressed element for operating said actuating bars.

9. A swinging railway gate including a post, a panel hinged to the post, an end section hinged to the panel, stops on the panel limiting the swinging of the panel in one direction, a sliding bolt on the panel adapted 125

to engage the section when the gate is swung to a closed position for locking said section against swinging, a spring on the section normally holding the bolt retracted from the section, and a fixed stop engaged by the bolt, whereby the latter is slid into locking engagement with the gate section.

10. In an automatic railway crossing gate, a plurality of swinging gates, an operating unit for said gates at the crossing, a rod on the rail for actuating said unit to close the gates, a tripping lever contiguous to the rail, a bell crank lever connected with said trip-

ping lever, and a forwardly directed link connecting the bell-crank lever with the rod. 15

11. In an automatic railway crossing gate, a plurality of swinging gates, an operating unit for said gates, a bar for actuating said unit to open the gates, a tripping lever contiguous to the rail, a bell crank lever, a 20 link connecting the levers, and a pitman connecting the bell crank lever with the bar.

In testimony whereof I affix my signature.

COCIU ENACHE.
